UNITED STATES PATENT OFFICE.

JOHN S. O'CONNOR, OF WHITE MILLS, PENNSYLVANIA, ASSIGNOR TO
C. DORFLINGER & SONS, OF SAME PLACE.

DESIGN FOR A DISH.

SPECIFICATION forming part of Design No. 16,676, dated May 4, 1886.

Application filed March 19, 1886. Serial No. 192,458. Term of patent 14 years.

To all whom it may concern:

Be it known that I, JOHN S. O'CONNOR, of White Mills, Wayne county, and State of Pennsylvania, have originated and produced 5 a Design for Dishes and other Articles of Table-Ware, of which the following is a specification.

I will describe my design, and then point out the novel features in the claim.

10 The accompanying illustration represents a top view of a disk embodying my design.

A designates a star-shaped figure in the center of the dish. Intersecting angular lines in the star-shaped figure form numerous facets.

15 Within the place where these lines intersect is a space in which is arranged a similar star or star-like figure, B. Outside the star A is a larger star-like figure, C, in which intersecting lines meet at angles and form numerous facets.

20 A polygonal figure, D, is in the central portion of the dish. Between the points of the star-shaped figure C scallop-shaped figures E are arranged. These figures E severally con-

sist of lines radiating from a common point toward the edge of the dish, and a scallop or 25 serrated portion at the ends of the lines.

In certain of the spaces in the points of the star-shaped figure C ornaments G are arranged. These ornaments G consist of numerous small diamond-shaped figures arranged in rows. In 30 certain other spaces in the points of the star-shaped figure C figures H are arranged. These figures consist of lines radiating from the points of the star-shaped figure C toward the center of the dish.

35 What I claim as my invention, and desire to secure by Letters Patent, is—

The design for the ornamentation of dishes, consisting of a dish having upon its surface a star, A, a star-shaped figure, C, and a polygonal 40 figure, D, substantially as shown and described.

JOHN S. O'CONNOR.
